(57) CLAIM

I claim the ornamental design for an Adinkra card game, as shown and described.

DESCRIPTION

FIG. 1 is a the front faces for an Adinkra card game showing my new inventions;

FIG. 2 is a second set of front faces thereof;

FIG. 3 is a third set of front faces thereof;

FIG. 4 is a fourth set of front faces thereof;

FIG. 5 is a fifth set of front faces thereof; and,

FIG. 6 is a sixth set of front faces thereof.

1 Claim, 6 Drawing SheetsFIG. 1

Adinkrahene Mercy 3	Akofena Courage 19,000	Akokonan Discipline 600
Akoma Love 6,000	Asase Ye Duru Providence 200	Aya Endurance 300
Besé Saka Resourcefulness 400	Bi Nka Bi Peace 40	Boa Me Na Me Mmoa Wo Cooperation 16,000

FIG. 2

 Dame Dame	 Denkyem	 Duafe
 Judgement	 Foundation	 Cleanliness
4 d	8 q	700 y
 Dwenauimmen	 Eban	 Epa
 Resilience	 Charity	 Justice
10 e	20 e	60 j
 Ese Ne Tekrema	 Fawohodie	 Fihankra
 Growth	 Kingship	 Security
30 i	9 f	800 z

FIG. 3

Fofo Transmutation 18,000	Funtunfune fu Denkyemfune fu Diversity 7,000	Gye Nyame God 0
Hwemidua Perfection 50	Hye Wonhye Imperishability 1,000	Kate Pa Faith 13,000
Kiminkantau Humility 70	Kwatakye Aliko Bravery 28,000	Mate Masie Prudence 11,000

FIG. 4

 Miframadan Fortitude 10,000	 Minerz Dane Constancy 80	 Mpatapo Reconciliation 90
 Mpuanum Skillfulness 5,000	 Musuyidee Enlightenment 21,000	 Nea Onnim No Sua A, Ohu Service 7
 Nkonesenkense Responsibility 8,000	 Nkyimu Precision 100	 Nkyinkyim Adaptability 12,000

 Nsaa	 Nsoroma	 Nyame Biribi Wa Soro
 Excellence	 Guardianship	 Beauty
4,000	14,000	5
 Nyame Dua	 Nyame Nnwu Na Mawu	 Nyansapo
 Knowledge	 Immortality	 Intelligence
